FUNGICIDAL PREPARATIONS

William O. Elson, West Chicago, Ill., assignor to The Kendall Company, Boston, Mass., a corporation of Massachusetts

No Drawing. Application March 26, 1956
Serial No. 573,649

7 Claims. (Cl. 167—58)

This invention relates to the control of fungus growth and particularly to improved fungicidal agents adapted to inhibit such growth.

It is a primary object of the invention to provide compositions of high fungicidal activity which are suitable for use on the human body and particularly for the control of fungus growth on the skin.

I have found that certain phenylmercapto compounds of the type hereinafter described are useful as the active ingredient in fungicidal compositions containing mixtures of such compounds with suitable diluents. For example, these compounds have been found to be excellent inhibitors of such pathological fungi as:

Candida albicans
Trichophyton mentagrophytes
Trichophyton gypseum
Trichophyton rubrum
Trichophyton purpureum
Trichophyton crateriforme
Trichophyton schoenleinii
Trichophyton tonsurans
Epidermophyton floccosum
Blastomyces dermatitidis
Microsporum canis
Microsporum gypseum
Microsporum fulvum
Microsporum audouini

In general, I employ as the active ingredient in my fungicidal compositions a compound having the general formula:

in which Ar is a phenyl group; Z represents hydrogen or an alkyl group containing from 1 to 5 carbon atoms; n is a numeral varying from 0 to 4; and X is hydroxyl, or a carbalkoxy group, in which the alkyl group contains from 1 to 3 carbon atoms.

To be useful as an inhibitor of fungus growth, an agent must be effective in such concentrations that the agent itself is not destructive of the material or living tissue to which it may be applied. The compounds of this invention are in general sufficiently mild to be substantially innocuous to the various materials to which they are applied, when used in the amounts necessary for inhibition of fungus growth. In general, compositions containing between 2% and 10% of the phenylmercaptoaliphatic compound are preferred. Where skin areas have become tender due to fungus infections, it is desirable to use concentrations in such treatment not higher than 15%. Concentrations higher than 15%, while effective in fungus growth inhibition, have a tendency to be too harsh for application to such tender raw areas.

The effectiveness of these compounds as inhibitors of

2

the fungi hereinbefore mentioned has been demonstrated by extensive in vitro tests. For example, tests were made upon the fungus *Candida albicans* which is a disease producing organism causing both superficial and systemic infections characterized by a high order of resistance to chemotherapy. The lack of sensitivity of *Candida albicans* to the inhibiting and fungicidal action of most antifungal agents has long been recognized. It can be taken as a general rule, therefore, with but few exceptions that any chemical agent active against *Candida albicans* will show a similar or greater activity against other pathogenic fungi.

Because *Candida albicans* grows well and quickly on artificial media, it lends itself particularly to the following effectiveness test. It is to be understood, however, that the test procedure is substantially the same when applied to other fungi.

TEST METHOD

Small volumes (.16-.25 cc.) of acetone solutions of varying concentrations of the fungicidal compound are added to a series of tubes containing sterile, melted Sabouraud's agar. The tubes are first shaken to disperse the compound and are then cooled in an inclined position to solidify the agar. In general, concentrations of 25, 12.5, 6.2, 3.1, 1.5, .7, .3 and .15 milligrams of the fungicidal compound per 20 cc. of media are obtained. The surface of the treated agar in each tube is then streaked with a one millimeter loop of a suspension prepared by suspending a 24-48 hour Sabouraud's agar culture of *Candida albicans* (or other fungus) in 2 cc. of sterile distilled water. The inoculated tubes are stored at room temperature for 48 hours and then checked for evidence of growth. The lowest concentration of acid which completely prevents growth measures the activity of the compound under test.

In the case of other fungi the test procedure is the same as described above, except that the aging period should be continued for at least 10 days.

In the following table the activity or effectiveness of representative compounds of the invention against various pathogenic fungi is given. The activity in each instance is represented in milligrams per 20 cc. of agar required to prevent growth, using the test method outlined above.

Table I

Compound	<i>Trichophyton gypseum</i>	<i>Trichophyton rubrum</i>	<i>Microsporum canis</i>	<i>Microsporum gypseum</i>	<i>Candida albicans</i>
50 Phenylmercapto-ethanol	12.5	12.5	6.2	6.2	25.0
55 Phenylmercapto-acetic acid methyl ester	12.5	6.2	6.2	6.2	6.2
55 Phenylmercapto-acetic acid ethyl ester					12.0

Twelve and a half milligrams in 20 cc. of agar represents a concentration in the range of .06% by weight. Although concentrations less than those indicated in Table I also tend to exert an inhibitory influence, the inhibition may be incomplete in the particular environment.

The preferred method by which I inhibit fungus growth is by utilizing a dusting powder in which the fungicidal agent is mixed with finely powdered diluent dusts such as talc, corn starch, rice, starch, kaolin, precipitated chalk, zinc oxide, zinc stearate, magnesium oxide and the like. Any generally non-toxic inert powder may be utilized as a diluent.

The following examples of fungus inhibitory dusts are given by way of illustration.

3
EXAMPLE 1

	Percent
Phenylmercaptoethanol	.3 to 10
Talc	99.7 to 90

EXAMPLE 2

Phenylmercaptoacetic acid ethyl ester	10
Talc	80
Corn starch	10

EXAMPLE 3

	Percent
Phenylmercaptoopropanol	10
Talc	60
Starch	20
Kaolin	10
	15

EXAMPLE 4

Phenylmercaptoethanol	10
Talc	50
Starch	20
Zinc oxide	20
	20

EXAMPLE 5

Phenylmercaptobutanol	2
Boric acid	6
Zinc stearate	3
Exsiccated alum	1
Starch	10
Talc	78

EXAMPLE 6

Phenylmercaptoacetic acid methyl ester	45
Talc	55

The fungicidal agent may also be applied by means of ointments, or by means of liquids, either in diluted or dispersed form, including for example sprays, vapors, solutions, emulsions and the like. In such cases the agent may be either in a volatile or non-volatile liquid carrier.

The following are representative examples of suitable ointments capable of inhibiting fungus growth:

EXAMPLE 7

	Percent
Polyethylene glycol (mol. wt. about 1600)	.99.8 to 85
Phenylmercaptoacetic acid ethyl ester	.2 to 15

EXAMPLE 8

Phenylmercaptoethanol	.2 to 15
Petrolatum	99.8 to 85

EXAMPLE 9

Phenylmercaptoacetic acid methyl ester	50
Petrolatum	50

The following are examples of useful fungus-inhibitory solutions:

EXAMPLE 10

	Percent
Acetone	99.5
Phenylmercaptoacetic acid ethyl ester	.5

EXAMPLE 11

95% Ethyl alcohol	98
Phenylmercaptoethanol	2

EXAMPLE 12

Acetone	95
Phenylmercaptoacetic acid methyl ester	5

EXAMPLE 13

Alpha-n-propylphenylmercaptoacetic acid methyl ester	.5
Acetone	99.5

EXAMPLE 14

Alpha-butylphenylmercaptoacetic acid methyl ester	2
95% Ethyl alcohol	98

The following is an example of a non-drying fungus-inhibitory solution:

4
EXAMPLE 15

Glycerine	90
Phenylmercaptoacetic acid ethyl ester	10

In some instances it is desirable to employ conventional propellant liquids as the carrier. By propellant liquids I refer to gaseous carriers which have been liquefied under pressure and have admixed therewith a solid or liquid agent. Such carriers, when released from confinement through a small orifice in the form of a fine spray, carry the liquid or solid agent with them, thereby serving as a propellant. The preferred materials for this purpose are the fluorinated hydrocarbon propellants, particularly derivatives of methane and ethane.

The following are examples of suitable propellant mixtures or solutions:

EXAMPLE 16

	Percent
Phenylmercaptoethanol	5
Isopropanol	5
Trichloro monofluoromethane	45
Dichloro difluoromethane	45

EXAMPLE 17

Dichloro tetrafluoroethane	93
Isopropanol	5
Phenylmercaptoacetic acid ethyl ester	2

EXAMPLE 18

Dimethyl ester	85
Ethyl alcohol	5
Alpha-phenylmercaptoopropanol	10

EXAMPLE 19

Carbon dioxide	92
Alpha-phenylmercaptobutanol	8

EXAMPLE 20

Ethyl chloride	95
Phenylmercaptoacetic acid methyl ester	5

The solutions of Examples 16 to 20 are all propellant mixtures which are applied under pressure from a conventional bomb type can.

Although it is usually preferable to employ between about 2 and 10% of the fungicidal agent in compositions intended for use on human skin, in some instances concentrations as high as 20% of the agent based on the total weight of the non-volatile constituents of the composition may be employed without harm. When the methyl ester of phenylmercaptoacetic acid is employed as the agent, concentrations as high as 50% may be used. Moreover, when applying the fungicidal agents of the invention to surfaces other than the skin, they may frequently be applied in higher concentrations to advantage. I claim:

1. The method of inhibiting the growth of pathogenic, parasitic fungus which comprises contacting a medium subject to said growth with a compound having the general formula:

in which Ar is a phenyl group; Z is a member selected from the group consisting of hydrogen and an alkyl radical containing from 1 to 5 carbon atoms; n is a numeral varying from 0 to 4; and X is a member selected from the group consisting of the hydroxy radical and a carbalkoxy radical in which the alkyl group contains from 1 to 3 carbon atoms.

2. The method of claim 1 in which the compound is phenylmercaptoacetic acid methyl ester.

3. The method of inhibiting the growth of pathogenic, parasitic fungus which comprises contacting the growth with a composition containing from 2 to 10% by weight of a compound having the general formula:

in which Ar is a phenyl group; Z is a member selected from the group consisting of hydrogen and an alkyl radical containing from 1 to 5 carbon atoms; n is a numeral varying from 0 to 4; X is a member selected from the group consisting of the hydroxy radical and a carbalkoxy radical in which the alkyl group contains from 1 to 3 carbon atoms; and from 90 to 98% of a carrier therefor.

4. The method of claim 3 in which the carrier is a non-toxic powdered diluent.

5. The method of claim 3 in which the carrier is a 10 non-toxic liquid diluent.

6. The method of claim 3 in which the carrier is a non-toxic propellant liquid.

7. The method of claim 3 in which the carrier is an ointment.
